WILLIAM K. LIGGETT, OF COLUMBUS, OHIO, ASSIGNOR TO THE JEFFREY MANUFACTURING COMPANY, OF COLUMBUS, OHIO, A CORPORATION OF OHIO.

PULVERIZING MACHINE.

Application filed June 8, 1923. Serial No. 644,166.

The present invention relates to certain new and useful improvements in pulverizing machines, of the class in which a rotor is arranged for rapid revolution within a casing to engage and pulverize the material therein.

The especial object of this invention is to provide an improved arrangement of parts whereby the journal bearings which support the rotor shaft will be effectively protected from finely divided abrasive material resulting from the operation of the machine.

The means by which I attain this object are fully set forth in the following specification, and illustrated in the accompanying drawings of which—

Fig. 1 is a side elevation of a pulverizing machine embodying my invention.

Fig. 2 is a sectional view taken along the line II—II of Fig. 1.

Fig. 3, is a fragmentary sectional view taken along the line III—III of Fig. 2.

Like numerals refer to similar parts in the several figures.

In the drawings the numeral 1 refers to a horizontally disposed shaft, supported in suitable bearings 2 which may be of any preferred construction but which are preferably ball bearings. The bearings 2 are supported upon the pedestals 3 which project upwardly from the main frame 4. The frame 4 is a hollow rectangular casting and supports, partly within its boundaries, a casing 5 within which the active elements of the machine are contained.

The active elements of the machine comprise a cylindrical rotor 6 from which project a plurality of pivotally mounted radially extending beaters 7 adapted, when the rotor revolves, to engage and pulverize material within the casing. The rotor 6 is composed of a series of discs 8 arranged in spaced relation to each other and fixed to the shaft 1, and the end discs 9 of the series are provided with hubs 10 which are keyed to the shaft 1. Aligned apertures extending through the entire series of discs, are adapted to receive the pivot bolts 11 upon which the beaters 7 are mounted.

The casing 5 is formed of the side walls 12 and 13 and the end walls 14, and a grating formed of longitudinally extending bars 15 serves as a bottom to hold the material within the effective path of the beaters until it is completely pulverized. These parts are

shaped to cooperate with the rapidly revolving beaters to pulverize material which may be introduced through the opening 16 at the top of the casing. A pulley 17 attached to the shaft 1 affords means for connecting the rotor with the power devices by which the machine is actuated.

Formed in the end walls 14 of the casing are apertures 18 through which the shaft 1 extends, and these apertures are shaped to afford convenient means for the inspection and renewal of the interior parts of the machine. Cover plates 19 removably secured to the end walls 14 closely approach the shaft 1 and close the apertures 18 to confine the material being pulverized to the interior of the casing. In order to avoid destructive friction, and to produce the desired smoothness of operation, there is necessarily provided a running clearance between the shaft 1 and cover plates 19 through which the finely divided material tends to escape from the interior of the pulverizing chamber. The pedestals 3 are so positioned upon the frame 4 that a clear space intervenes between the bearings 2 and the cover plates 19, thereby preventing finely divided material from following along the shaft into the interior of the journal bearings.

For convenience of manufacture the end walls 14 of the casing are formed of relatively soft metal, poorly adapted to withstand the abrasive action of the material which is being pulverized within the casing.

To prevent rapid deterioration of the machine the inner surfaces of the casing are protected by suitable lining plates composed of a highly refractory alloy of iron. The end walls 14 of the casing are protected by the lining plates 20 and 21 which are secured in place by properly designed attachment bolts 22. The plates 20 and 21 may be formed for convenient assemblage with the rest of the machine in the manner shown in Fig. 2 of the drawing, where it will be observed they are made so as to abut on a vertical line traversing the axis of the rotor. The plates 20 and 21 are shaped to form circular cavities at each end of the casing and the end discs 9 of the rotor are provided with longitudinally projecting cylindrical annular flanges 24 which extend into these cavities. The surfaces 25 of the inner edges of the upper lining plates 20 are of cylindrical contour extending parallel to the shaft 113

1, and closely approach the cylindrical outer surface of the flanges 24, while the corresponding surfaces 26 of the lower lining plates 21 are of conical contour inclined inwardly from the shaft. By this arrangement of the parts the openings 18 in the end walls of the casing are substantially closed by the flanged end disks 19, so that particles of material which work outwardly between 10 the flanges 24 and the plates 20 or which collect upon the flanges 24 are carried around by the rotation of the flanges 24 and are dropped upon the inclined surfaces 26 of the plates 21 and deflected by them onto the 15 grating 15 and are discharged with the finished product between the grate bars.

By the arrangement of parts above described the machine is adapted to the pulverization of abrasive material without 20 danger of dust and dirt escaping, to any injurious extent, from the substantially closed casing, and the journal bearings upon which the rotor is supported are so thoroughly protected from the finely divided 25 material which tends to escape through the smallest crevices of the casing that relatively expensive and delicate ball bearings may be economically used, thereby permitting the rotor to revolve at extremely high velocities 30 and with minimum power consumption.

What I claim is:—

1. In a machine of the class described, the combination of a casing having an opening through a portion of its end wall to 35 permit access to the interior of said casing, a shaft traversing said casing with its end projecting through the opening, bearings for said shaft spaced from said casing to provide a working area, and a disk rotating 40 with said shaft and lying closely adjacent the opening with its periphery in close proximity to the circumferential wall of said opening.

2. In a machine of the class described, the combination of a casing having an opening through the upper portion of its end wall to permit access to the interior of said casing, a shaft traversing said casing with 45 its end projecting through the opening, bearings for said shaft spaced from said casing to provide a working area, a disk rotating with said shaft and lying closely adjacent the opening with its periphery in close proximity to the circumferential wall of said opening, and an exterior cover for said opening.

3. In a machine of the class described, the combination of a casing having an opening through the upper portion of its end 50 wall, an abutment on the casing wall below said opening inclined inwardly toward the interior of the casing, a shaft traversing said casing with its end projecting through the opening, bearings for said shaft spaced from 55 said casing to provide a working area, a

disk rotating with said shaft, and a horizontal flange on said disk closely adjacent the opening with its periphery in close proximity to the circumferential wall of said opening. 70

4. In a machine of the class described, the combination of a casing having an opening through the upper portion of its end wall, the circumferential wall of which is cylindrical above the horizontal center of 75 the casing and the vertical wall of which is inclined inwardly toward the interior of the casing below said horizontal center, a rotor in said casing, bearings for said rotor, and a cylindrical part on said rotor closely 80 adjacent said opening with its periphery in close proximity to the circumferential wall of said opening.

5. In a machine of the class described, the combination of a casing having an opening 85 in the upper portion of its end wall to permit access to the interior of said casing, a shaft traversing said casing with its end projecting through the opening, bearings for said shaft spaced from the casing to provide a working area, a liner plate secured to the inner face of said end wall and having a circumferential opening 90 therein, and a disk rotating with said shaft and lying within the opening in said liner with its periphery in close proximity to the circumferential wall of the liner opening. 95

6. In a machine of the class described, the combination of a casing having an opening 100 in the upper portion of its end wall to permit access to the interior of said casing, a shaft traversing said casing with its end projecting through the opening, bearings for said shaft spaced from the casing to provide a working area, a liner plate secured to the inner face of said end wall and having a circumferential opening 105 therein, the peripheral wall of which is inclined inwardly and downwardly through a portion of its circumference, and a disk rotating with said shaft and lying within the opening in said liner with its periphery in close proximity to the circumferential wall of the liner opening. 110

7. In a machine of the class described, the combination of a casing having an opening 115 in the upper portion of its end wall to permit access to the interior of said casing, a shaft traversing said casing with its end projecting through the opening, bearings for said shaft spaced from the casing to provide a working area, a vertically divided liner plate of relatively hard material secured to the inner face of said end wall and having a circumferential opening 120 therein, and a disk rotating with said shaft and lying within the opening in said liner with its periphery in close proximity to the circumferential wall of the liner opening. 125

8. In a machine of the class described, the combination of a casing having an opening in the upper portion of its end wall to permit access to the interior of said casing, a shaft traversing said casing with its end projecting through the opening, bearings for said shaft spaced from the casing to provide a working area, a vertically divided liner plate of relatively hard material secured to the inner face of said end wall and having a circumferential opening therein, a disk rotating with said shaft and lying within the opening in said liner with its periphery in close proximity to the circumferential wall of the liner opening, and a cover plate for the opening in the end wall of said casing.
- 5 In testimony whereof I have hereunto set my hand.
- 10 WILLIAM K. LIGGETT.
